Primary Examiner — Cynthia Underwood(74) *Attorney, Agent, or Firm* — K&L Gates LLP(57) **CLAIM**

The ornamental design for a cup, as shown and described.

DESCRIPTION

FIG. 1 is a front perspective view of the cup;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof. The part of the photograph shown in a coarse dot pattern, along with the broken-line perimeter, illustrates a portion of the cup that forms no part of the claimed design.
